Primary Examiner—Antoine Duval Davis*Attorney, Agent, or Firm*—Harold H. Dutton, Jr.[57] **CLAIM**

The ornamental design for a water level adjuster for swimming pools, as shown and described.

DESCRIPTION

FIG. 1 is a perspective view of the measuring portion of a water level adjuster for swimming pools showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view of the housing portion thereof;

FIG. 9 is a front view thereof;

FIG. 10 is a rear view thereof;

FIG. 11 is a left side view thereof; The right side is a mirror image thereof;

FIG. 12 is a top view thereof;

FIG. 13 is a bottom view thereof;

FIG. 14 is a perspective view of both portions thereof; and,

FIG. 15 is a view of the complete water level adjuster.
